CLAIM

The ornamental design for a pocket guard, as shown and described.

DESCRIPTION

FIG. 1 is a front elevational view of the pocket guard showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a reduced front elevational view thereof shown in the position of use, the broken lines partially showing trousers being for illustrative purposes only and forming no part of the claimed design.
